FASTENER-FEEDING AND HOLDING MECHANISM FOR POWER-DRIVEN FASTENER TOOLS

Otmar M. Ulbing, Lisle, N.Y., assignor to Ingersoll-Rand Company, New York, N.Y., a corporation of New Jersey

Filed Oct. 2, 1964, Ser. No. 400,998
16 Claims. (Cl. 144—32)

This invention relates to power tools and more particularly to fastener-feeding and holding means for power tools.

Presently known power tools, such as power screw drivers, employ a "Y"-type connecting joint between a screw feed conduit and the housing of the tool to convey the fasteners into the finder of the tool in front of the driving bit of the tool. This construction is undesirable since the driving bit must be retracted a substantial distance to permit the passage of the fastener into the finder. This reciprocation is undesirable since it requires an excessive amount of useless movement or "dead stroke" of the tool. To minimize the problems involving the guidance of the fasteners into the finder, the "Y"-type connection is constructed and arranged so that the entry passage axis is located at as small an acute angle as possible with respect to the longitudinal axis of the bit. This latter requirement further aggravates the amount of useless movement of the bit required to permit the passage of the fastener into the finder.

In addition to the aforementioned disadvantages, escapement mechanisms are required at the finder to insure entry of the fasteners singly into the finder, which mechanisms are relatively complex and subject to malfunctions. Also, means had to be provided to prevent the fasteners from being forced back from the finder jaws at the start of the driving operation of the tool.

Accordingly, it is an object of this invention to provide for a power tool a fastener-feeding mechanism wherein in useless or "dead stroke" movement of the bit is minimal.

Another object of the present invention is to provide a fastener-feeding mechanism which is capable of feeding fasteners of a greater range of different sizes than presently known mechanisms.

A further object of this invention is to provide a fastener-feeding mechanism wherein a separate means to prevent the fastener from being forced out of engagement with the finder jaws at the start of the driving of the tool is obviated.

In brief, the objects of this invention are accomplished in a fastener driving tool having a fastener-feeding mechanism by mounting the fastener driving bit of the tool on a flexible shaft and arranging it to be forced laterally out of axial alignment with the tool by the feeding of a fastener through the screw feed conduit, thus uncovering the discharge end of the conduit whereby a fastener can pass freely from the conduit into the finder of the tool without interference by the tool bit.

In one embodiment of the invention the tool bit is moved laterally under the urging of the pressurized fluid in the fastener-feeding conduit, which fluid impinges the surface of a tubular member containing the tool bit covering the entrance port.

In another embodiment of the invention the tubular member carrying the tool bit is provided with a canted piston which, when subjected to the pressurized fluid, causes the tubular member to move laterally and uncover the entrance port.

The invention will be more fully understood from the following detailed description thereof when considered

in connection with the accompanying drawings wherein two embodiments of the invention are illustrated by way of example and in which:

5 FIG. 1 is a fragmentary, side elevational view of a power tool having a fastener-feeding mechanism according to one embodiment of this invention;

FIG. 2 is a longitudinal, sectional view taken along line 2—2 of FIG. 1;

10 FIG. 2A is a fragmentary view of the rear portion of the power tool to which the fastener-feeding mechanism shown in FIG. 2 is joined along line A—A;

FIG. 3 is a perspective view, with parts broken away, showing the fastener-feeding mechanism shown in FIG. 1;

15 FIG. 4 is an exploded, perspective view, similar to FIG. 3, having a greater number of parts broken away for illustrative purposes;

FIG. 5 is a perspective view, similar to FIG. 3, with other parts broken away for purposes of illustration;

20 FIG. 6 is a schematic and vertical section of the tool showing the fastener driving bit forced to tilt sideways to uncover the end of the fastener feed tube during the feeding of a fastener;

25 FIG. 7 is another schematic and vertical section of the tool taken at right angles relative to FIG. 6 and showing a fastener being held by the fastener-holding jaws in position for being driven;

FIG. 8 is a schematic view similar to FIG. 7 showing the tool as the fastener is released by the jaws and driven "home"; and

30 FIG. 9 is a view, similar to FIG. 2, showing another embodiment of the present invention.

Referring now to the drawings and particularly to FIGS. 1 to 8, the reference numeral 10 generally designates the fastener-feeding and holding mechanism according to this invention, which mechanism is shown connected, for purposes of illustration, to a screw fastener power tool 11.

As best shown in FIGS. 1, 2 and 2A, power tool 11 comprises a housing or casing 12 in which is disposed a motor (not shown) connected to rotatively drive a bit holder 14. A tubular shroud 15 is coextensive with casing 12 and supports, for slidable movement relative to the casing, a fastener feed tube 16. As shown in FIG. 2A, a pressurized fluid supply tube 17 is connected 40 at one end to casing 12 and at the opposite end to a source of pressurized fluid, such as compressed air. The porting and passageways (not shown) are provided in casing 12 to communicate supply tube 17 with the motor (not shown) so as to effect rotation of the latter. A 45 slide valve 18 is mounted on supply tube 17 and is connected to fastener feed tube 16 so as to move with the latter and relative to supply tube 17. The construction, function, and purpose of slide valve 18 will be more 50 fully described hereinafter.

Fastener-feeding and holding device 10, as best shown in FIGS. 1 to 5, includes a housing extension 19 which is coaxially secured to casing 12. A finder housing 20 is provided with a cylindrical bore 21 in the rear end portion 22 thereof, which bore is dimensioned to slidably 55 receive housing extension 19 therein so that the finder housing is supported for axial movement relative to the housing extension 19. As best shown in FIGS. 1 and 60 3, finder housing 20 is provided with a slot 23 extending from one side to the other and from rear end portion 22 to the distal end portion 24 so that the finder housing is bifurcated and thereby has a pair of finger portions 25 and 26. An oval-shaped fastener entrance port 27 is provided in finger 26 to receive the discharge 65 end portion of fastener feed tube 16 (see FIG. 4). A pair of jaws 28 and 29 is pivotally disposed in slot 23 by pins 30 which extend through the registered openings 70 75 80 85 90 95 100 105 110 115 120 125 130 135 140 145 150 155 160 165 170 175 180 in fingers 25 and 26 and jaws 28 and 29. Jaws 28 and 29 are biased in a closed position by springs 31 which are secured in openings 32 in end portion 22 by set screws 33 and which project into a groove 34 in each of the jaws 28 and 29. The jaws 28 and 29 have complementary-shaped, juxtaposed gripping faces 35 and 36, respectively, which define therebetween a fastener-receiving and holding orifice.

Disposed in slot 23 between jaws 28 and 29 is an elongated bit guide 38 which comprises in cross section a substantially square portion 39 and an integral cylindrical portion 40. The end of cylindrical portion 40 is provided with an enlarged flanged end 41. Flanged end 41 is dimensioned to fit loosely within housing extension 19 so that bit guide 38 can tilt laterally out of axial alignment with the tool as illustrated in FIGS. 4 and 6. A snap ring 45 serves to retain bit guide 38 within housing extension 19 by abutting flanged end 41. Bit guide 38 has a cylindrical axial bore 42 extending therethrough, which bore is adapted to receive a fastener-engaging member or bit 43. Bit 43, as illustrated, may be a screw driver bit which is secured at one end to the end of a flexible shaft or shank member 44. The rear end portion of shank member 44 is adapted to fit within and to be rotatively secured to bit holder 14. Bit guide 38 is biased in a forward direction by a coil spring 46 which is disposed within housing extension 19 and in abutment at one end against an end wall 19A and flanged end 41 of bit guide 38.

To permit lateral, pivotal movement of bit guide 38 and bit 43 in a direction away from entrance port 27, finger 25 is provided with a rectangular-shaped notch 47. Notch 47 is dimensioned so as to permit movement of bit guide 38 therethrough, as is illustrated in FIG. 4. Spring 46, upon pivotal movement of bit guide 38, is loaded and thereby urges bit guide 38 to return to a position in which it covers entrance port 27 and aligns with the fastener-receiving and holding orifice defined by jaws 28 and 29.

To prevent lateral movement of bit guide 38 while the power tool is in the fastener-rundown position shown in FIG. 5, each of the jaws 28 and 29 is provided with lugs or projections 28A and 29A, respectively, which engage shoulders or rabbets 38A and 38B, respectively, formed on bit guide 38. Projections 28A and 29A are so dimensioned that they only engage their respective shoulders 38A and 38B when pivoted to an open position as is shown in FIGS. 5 and 8.

The projections 28A and 29A on the jaws 28 and 29 also serve to prevent the jaws 28 and 29 from opening during the feeding of a screw or other fastener. When the bit guide 38 is in its normal position of axial alignment with the tool, the rabbets 38A and 38B receive the jaw projections 28A and 29B when the jaws 28 and 29 open, as shown in FIGS. 5 and 8. However, the tilting of the bit guide 38 to uncover the feed tube 16, as shown in FIGS. 4 and 6 swings the sides of the bit guide 38 between the jaw projections 28A and 29A, thus engaging and preventing the jaws 28 and 29 from opening.

In other words, the tilting of the bit guide 38 to the fastener feeding position shown in FIG. 6 swings the rabbets 38A and 38B out of position to receive the jaw projections 28A and 29A, so that the jaws 28 and 29 are locked in closed position. This feature prevents the jaws 28 and 29 from opening during the feeding of a fastener. Opening the jaws 28 and 29 at this time would allow the fastener to escape from the gripping faces 35 and 36 of the jaws 28 and 29 and be "shot" from the tool.

In the operation of fastener-feeding and holding device 10, a fastener 50 (FIG. 1) is delivered from a source of fasteners along with the pressurized fluid, such as air, through an escapement mechanism (not shown) into a flexible portion (not shown) of feed tube 16. The pressurized fluid acts on the surface of bit guide 38 cover-

ing entrance port 27 and thereby forces the bit guide 38 to tilt laterally into notch 47 of finger 25, as shown in FIG. 6. The bit guide 38 is tilted sufficiently to uncover the port 27 and permit fastener 50 to pass through entrance port 27 into the space between jaws 28 and 29 and into the fastener-receiving and holding orifice defined by gripping faces 35 and 36 of jaws 28 and 29, as shown in FIG. 7. Thereafter, the tool is moved toward a working surface 52 and into engagement with the latter, as shown in FIG. 8, so that the entire fastener-feeding and holding mechanism 10 is moved rearwardly relative to power tool 11 and bit 43. Such movement brings bit 43 into engagement with the fastener which is prevented from moving rearwardly out of the receiving and holding orifice by the abutment of the forward end of bit guide 38 against the fastener. Continued axial movement of the fastener-feeding and holding mechanism 10 relative to bit 43 causes jaws 28 and 29 to be cammed apart by tapered end edges 51 of bit guide 38. The bit 43 is rotated by the power tool motor (not shown) through bit holder 14 and flexible shank 44 to thereby rotatively drive the fastener. When the fastener is secured in a working surface (not shown) to a predetermined extent, an escapement mechanism (not shown) is energized by a fluid signal conveyed to the mechanism by way of signal line 54 connected to slide valve 18 (see FIG. 2A). When slide valve 18 is carried rearwardly by feed tube 16 relative to supply tube 17 a sufficient distance to bring port 55 of supply tube 17 into communication with port 56 and passageway 57 in slide valve 18, the pressurized fluid flows from the interior of supply tube 17 to an escapement mechanism (not shown). This pressurized fluid signal energizes or conditions the escapement mechanism so that when fastener-feeding and holding mechanism 10 returns to an extended position, the escapement mechanism operates to allow another fastener and the pressurized fluid to flow into feed tube 16.

In FIG. 9 is shown another embodiment of the present invention, which embodiment differs from the embodiment shown in FIGS. 1 to 5 in that bit guide 38 is positively displaced rather than displaced coincidental with the pressurized fluid flowing through fastener feed tube 16. In view of the similarity of construction between the two embodiments, parts of the embodiment shown in FIG. 9 corresponding to or similar to the parts of the embodiment shown in FIGS. 1 to 5 will be designated by the same reference number but with the suffix Z added thereto.

As shown in FIG. 9, the feeding and holding mechanism 10Z has a bit guide 38Z having a canted piston head 60 in place of flanged end 41. A pressurized fluid supply line 61 is attached at one end to housing extension 19Z to communicate with the interior of the housing extension and at the opposite end with a suitable source of pressurized fluid (not shown). Spring 46 of the embodiment of FIGS. 1 to 5 has been replaced by a leaf spring 62 which is secured to end portion 22Z so as to extend into notch 47Z and into engagement with bit guide 38Z to bias the latter in a direction to close entrance port 27Z.

The opposite end (not shown) of line 61 may be connected to the escapement mechanism (not shown) so that when the escapement mechanism is actuated to introduce a fastener into feed tube 16Z, the pressurized fluid is introduced through line 61 into the interior of housing extension 19Z. When the pressurized fluid, such as compressed air, is introduced into housing extension 19Z, the force exerted by the fluid upon piston head 60 causes bit guide 38Z to be laterally displaced against the force of leaf spring 62. Displacement of bit guide 38Z, as in the embodiment described in FIGS. 1 to 5, uncovers entrance port 27Z to thereby permit passage of a fastener into the fastener-holding orifice defined between jaws 28Z and 29Z (only one of which is shown in FIG. 9).

It is believed now readily apparent that the present in-

vention provides a novel fastener-feeding and holding mechanism wherein useless or "dead" axial movement of the bit is eliminated. It is a mechanism wherein a fastener cannot be dislodged from the fastener-holding jaws until after firm engagement of the bit with the fastener is achieved.

Although only two embodiments of the invention have been illustrated and described in detail, it is to be expressly understood that the invention is not limited thereto. Various changes can be made in the arrangement of parts without departing from the spirit and scope of the invention, as the same will now be understood by those skilled in the art.

I claim:

1. In a power-driven, fastener-driving tool having a driven means mounted for rotation in a housing and connected to a source of rotary power, a fastener-feeding and holding mechanism comprising:

- (a) a finder mounted on said housing for axial movement relative to the latter,
- (b) said finder having an axial bore and at least a pair of jaws on either side of said bore for engaging a fastener,
- (c) said finder having an entrance port communicating with said bore,
- (d) conduit means connected at one end to a source of pressurized fluid and a source of fasteners and at the opposite end communicating with the bore at the entrance port in said finder,
- (e) a tubular member disposed in the bore of the finder and substantially covering said entrance port,
- (f) means for causing said tubular member to be displaced away from said entrance port and to allow passage of a fastener from said conduit means into said bore and toward the entrance port to substantially close said entrance port,
- (g) a fastener-engaging bit disposed in said tubular member, and
- (h) a flexible connecting means for connecting said fastener-engaging bit to said rotary driven means to thereby effect rotation of the bit and conjoined displacement of the bit with the tubular member.

2. The apparatus of claim 1 wherein said finder is bifurcated to define two fingers and said pair of jaws is pivotally mounted between said fingers.

3. The apparatus of claim 1 wherein said tubular member is substantially square in cross section and has a circular, interior configuration.

4. The apparatus of claim 1 wherein a spring is provided for biasing said tubular member in a direction toward the entrance port.

5. The apparatus of claim 1 wherein means connected to said housing is provided to define a cylinder in which one end of said tubular member is disposed.

6. The apparatus of claim 1 wherein cylinder means is connected to said housing and in which one end of said tubular member is secured, and spring means is disposed in said cylinder means to bias said tubular member toward said entrance port.

7. In a power-driven, fastener-driving tool having a driven means mounted for rotation in the housing of the tool and connected to a source of rotary power, a fastener-feeding and holding mechanism comprising:

- (a) a housing extension connected at one end to the housing,
- (b) a finder having an axial bore to be slidably receivable on the housing extension and an entrance port communicating with the bore,
- (c) at least a pair of jaws mounted on said finder for holding a fastener,
- (d) conduit means connected at one end to a source of pressurized fluid and a source of fasteners and at the opposite end to said finder so as to communicate with the axial bore through the entrance port in the finder,

(e) a tubular member disposed in the bore of said finder with one end thereof receivable in said housing extension,

(f) means for retaining said tubular member end in said housing extension,

(g) means for causing said tubular member to be laterally displaced from said entrance port and to allow passage of a fastener from the conduit means into said bore and toward the entrance port to substantially close said entrance port,

(h) a fastener-engaging bit disposed for rotation within said tubular member, and

(i) a flexible connecting means for connecting said fastener-engaging bit to said rotary driven means to provide rotation of the bit and allow conjoined lateral displacement of the bit with the tubular member.

8. The mechanism of claim 7 wherein spring means is provided to bias the tubular member in a direction to substantially close the entrance port.

9. The mechanism of claim 7 wherein pressurized fluid conduit means is provided for conducting the pressurized fluid to said housing extension and thereby effecting lateral displacement of the tubular member under the force of said fluid pressure.

10. The mechanism of claim 7 wherein said tubular member is provided at its distal end with camming means for actuating said pair of jaws to release a fastener held thereby.

11. In a power-driven, fastener-driving tool having a driven bit holder mounted for rotation in the housing of the tool and connected to a source of rotary power, a fastener-feeding and holding mechanism comprising:

- (a) a tubular housing extension connected at one end to the housing,
- (b) a finder having an axial bore to be slidably receivable on the housing extension and an entrance port communicating with the bore,
- (c) at least a pair of jaws pivotally mounted on said finder on opposite sides of said bore for holding a fastener,
- (d) a fastener-feed passageway communicating at one end to a source of pressurized fluid and a source of fasteners and at the other end with the entrance port of said finder,
- (e) a tubular member disposed in the bore of said finder with one end of the tubular member receivable in said tubular housing extension,
- (f) means for retaining said tubular member end in said housing extension,
- (g) a slot in said finder on the opposite side of the tubular member from said entrance port to permit lateral displacement of the tubular member in a direction away from said entrance port when so urged by the pressurized fluid in said conduit means,
- (h) biasing means for urging the tubular member in a direction to substantially cover said entrance port,
- (i) a fastener-engaging bit disposed for rotation within said tubular member, and
- (j) a flexible connector for coupling said fastener-engaging bit to said bit holder to provide rotation of the bit and allow conjoined lateral displacement of the bit and the tubular member.

12. The apparatus of claim 11 wherein said biasing means is a spring disposed in the housing extension and bearing against the end of the tubular member in said housing extension.

13. The apparatus of claim 11 wherein said biasing means is a leaf spring secured at one end to the finder and with the opposite end bearing against the tubular member.

14. The apparatus of claim 11 wherein said jaws have lugs which engage the tubular member when the jaws are pivoted to an open position to thereby prevent lateral displacement of the tubular member.

15. A fastener driving tool having a fastener feeding means comprising:

- (a) a frame including means for holding a fastener in position to be driven and being able to release a fastener as it is driven;
- (b) a motor mounted on said frame;
- (c) a fastener driving bit located in said frame in position to drive a fastener supported in said fastener holding means;
- (d) a fastener feeding conduit for feeding fasteners to said fastener holding means and having an outlet normally closed by said fastener driving bit; and
- (e) yieldable means connecting said fastener driving bit to said motor to be driven thereby and allowing said bit to tilt sideways to uncover said outlet of said

fastener feeding conduit during the feeding of a fastener.

16. The fastener driving tool of claim 15 including means for locking said fastener holding means against release during the time that said bit is tilted to uncover the outlet of said fastener feeding conduit.
